UNITED STATES PATENT OFFICE.

GEORGE T. OPLINGER, OF SLATINGTON, PENNSYLVANIA.

LOCK.

SPECIFICATION forming part of Letters Patent No. 739,556, dated September 22, 1903.

Application filed January 21, 1903. Serial No. 140,011. (No model.)

To all whom it may concern:

Be it known that I, GEORGE T. OPLINGER, of Slatington, in the county of Lehigh and State of Pennsylvania, have invented certain new and useful Improvements in Locks; and I hereby declare that the following is a full, clear, and exact description thereof, reference being had to the accompanying drawings, which form part of this specification.

10 This invention is an improved drop-handle lock especially designed for use on refrigerator-doors and combining the features of a pull, a latch, and lock in one device.

The invention consists in the novel construction of the lock, as hereinafter claimed, and illustrated in the accompanying drawings, in which—

Figure 1 is a face view of the complete lock. Fig. 2 is a view thereof with the back plate removed. Fig. 3 is a view on line 3 3, Fig. 2; and Fig. 4 is a detail. Fig. 5 is a detail view of a slight modification of the tumbler and means for holding same in unlocked position.

The box-like casing A has projecting perforated ears a on its ends, by which it can be fastened in position by suitable screws. It is closed by a removable back plate A' and on its front are provided forwardly-projecting ears a', between which is hinged the upper end b of the handle or pull B, which preferably has its lower end b' weighted, so that it will assume its normal position by gravity. The upper part b of the handle is provided with an inwardly-projecting lug b², which engages the outer end of a lug c, projecting from the front face of the latch-piece C, which is pivoted on a pin D and oscillates transversely of the casing, having a curved catch portion C' projecting outwardly through the side of the casing and adapted to engage a suitable keeper. (Not shown.) The lug c is close to the pivot of the latch, so that the movement of the end of piece C' will be greater than that of lug c. Lug c extends through an opening a² in the front of the casing adjacent to lug b' and in position to be engaged by the latter when the lower end of handle C is drawn outwardly. The latch C is normally forced outwardly (so as to press lug c upward against lug b²) by means of a spring E, which is placed between the side of casing and stem of the latch, having the

pivot of the latch-piece as its fulcrum and its lower end pressing against a stud or lug e in the casing and its upper end confined in a notch c' in the latch above the pivot thereof, as shown.

Within the casing, at the side of latch C opposite the catch C', is the locking-tumbler F, which is vertically movable and provided with slots f f, engaging studs or pins a³ a³ in the casing. The lower slot f has an offset f' at its lower end, which is held in engagement with the pin a³ when the tumbler is in its uppermost position by the action of the flat spring G, as shown in Fig. 2. The tumbler has a projection F' on its upper end, adapted to engage and lock the latch-piece when the tumbler is lowered. The tumbler also has a key-notch F² on its lower end, which is adapted to be engaged by the wing h of a key H, by turning which key the tumbler can be raised and lowered. When the tumbler is in raised position, as indicated in Fig. 2, by turning key H properly the lower end of the tumbler will be first forced outward, compressing spring G and disengaging notch f' from pin a⁴, and then the tumbler is drawn downward into locking position. On reverse rotation of the key the tumbler is raised until notch f' is opposite pin a⁴, whereupon spring G swings the tumbler so as to engage notch f' with pin a⁴, thereby upholding the tumbler in uppermost unlocked position. It will be observed that in the construction shown the catch is projected by the spring independently of the handle, but is retracted by a pull on the handle. The locking-tumbler is normally left in unlocked position, but may be lowered at will by a suitable key.

Having thus described my invention, what I therefore claim as new, and desire to secure by Letters Patent thereon, is—

In a combined lock and latch, the combination of the casing, a vertical latch pivoted therein having a forwardly-extending lug on its lower end at one side of its pivot projecting out of the casing, and a laterally-projecting catch on its upper end extending out of the side of the casing, a swinging handle or pull pivoted to the front casing and having a lug adapted to engage the lug on the latch when the handle is swung outwardly, and a spring for returning the latch to nor-

mal position, with a vertically-movable locking-tumbler within the casing, adjacent to the latch provided with longitudinal slots engaging guide-pins in the casing, one of said slots having a notch in its side adapted when engaged with the adjacent pin to uphold the tumbler in unlocking position, a spring for moving the tumbler laterally when in unlocking position so as to engage its notch with the pin, and a key-notch in the tumbler

whereby it can be operated by a key, all constructed and adapted to operate substantially as described.

In testimony that I claim the foregoing as my own I affix my signature in presence of 15 two witnesses.

GEORGE T. OPLINGER.

In presence of—

H. A. SCHERTZINGER,
S. D. BEHLER.
